UNITED STATES PATENT OFFICE

DALE O. MILLER, OF DETROIT, MICHIGAN

AUTOMATIC REGULATOR FOR STOKERS

Application filed May 28, 1928. Serial No. 281,324.

This invention relates to stokers and more particularly to improvements in the regulating means for hydraulic stokers.

It is one of the primary objects of this invention to automatically vary the speed of the hydraulic motor for actuating the stoker in accordance with variations in the load on the furnace.

Another object of this invention is to provide regulating means of the above character capable of operation independent of the fluid supply pump and actuating means therefor so that the pump may be run at a constant speed.

15 The invention further contemplates an arrangement whereby the draft inducing means and damper are controlled by the regulating means.

Other objects, advantages and novel details of construction of this invention will be made more apparent as this description proceeds especially when considered in connection with the accompanying drawings wherein:

25 Figure 1 is a perspective view of a stoker embodying my invention;

Figure 2 is a sectional detail view of the automatic regulating valve.

In general there is illustrated in Figure 1 of the drawings, a steam boiler 10 fired by an underfeed stoker 11. The latter is preferably of the reciprocating type, having a ram for feeding the coal from the hopper into the furnace in accordance with the usual practice. The ram or coal feeder illustrated herein is operated by a suitable hydraulic motor 12. The fluid for operating the motor is derived from a conventional pump 13 and the normal flow of the fluid is through the conduits 14, motor 12, outlet conduit 15, conduit 16 to the reservoir 17 and down through the standpipe 18 back to the pump.

45 For controlling the amount of fluid admitted to the hydraulic motor 12 to thereby regulate the frequency of operation of the ram or coal feeder, I provide a by-pass 19 connected at one end to the delivery side of the pump and at the other end to the reservoir 17. Arranged within the by-pass 19 is

a suitable valve 20 having an operating lever 21 disposed between the adjustable stops 22. Connected to the operating lever 21 by means of the cable 23 is a suitable expandible chamber or damper regulator 24 operated by the steam pressure from the pipe 25 and set for operation at any predetermined boiler pressure. As will be apparent from Figure 1 of the drawing the cable 23 is provided with extensions 26 and 27 connected to the damper 28 and louver 29 respectively, the arrangement being such that the expandible chamber in addition to controlling the speed of the hydraulic motor, regulates the damper 28 and the amount of air furnished to the furnace for combustion. The louver 29 and damper adjustments are effected simultaneously and in accordance with the adjustment of the hydraulic motor so that the proper draft will be furnished the furnace at all times.

The air for combustion is furnished by a fan 30 driven by any suitable prime mover as for example, the electric motor 31 which as shown also drives the pump 13. The outlet for the fan being through a suitable outlet box 32 communicating with the interior of the furnace in the customary manner and controlled by the louver 29.

In order to effect a manual adjustment of the hydraulic motor I provide a by-pass 33 extending around the valve 20 and connecting into the pipe 19. This by-pass is controlled by a suitable manually operated valve 34. Thus it will be apparent that the by-pass 33 functions as a fixed by-pass capable of effecting a change in speed of the hydraulic motor independent of the steam pressure. It will further be noted that this latter arrangement, as well as the automatic regulating means hereinbefore set forth is capable of varying the speed of the hydraulic motor independent of the driving means 31. In other words with the present invention, the speed of the ram or coal feeder may be varied proportionate to the load without varying the speed of the motor 31.

For controlling the pressure of the motor operating fluid a suitable pressure relief valve 35 is provided in the pipe 36 which,

as, shown communicates at one end with the supply pipe 14 and at the opposite end with the reservoir 17, the arrangement being such that if for any reason the stoker is stalled the pressure built up by the motor operating fluid in the pipe 14 will cause the valve 35 to open and permit the fluid to escape into the reservoir.

Referring now to the operation, it will be noted that whenever the steam pressure rises the expansible chamber 24 is expanded thereby opening the valve 20 and allowing a larger amount of fluid to by-pass through the pipe 19 back to the reservoir 17 and consequently reducing the speed of the hydraulic motor 12 proportionate to the amount of fluid by-passed. On the other hand, when the steam pressure is lowered, the chamber is contracted, thus closing the valve 20 and increasing the amount of fluid pumped through the hydraulic motor 12 and consequently increasing the speed of the hydraulic motor and the amount of coal forced into the furnace. In this connection it will be noted that at the same time the speed of the hydraulic motor is increased the louver 29 is opened supplying more air for combustion to take care of the extra fuel fed into the furnace. The damper 28 is also opened to permit the exhaust gases to escape through the stack.

Having thus revealed this invention, I claim as new and desire to secure the following combinations by Letters Patent of the

United States.

What I claim as my invention is:

1. In combination, a furnace having a stoker, a fluid operated motor for actuating said stoker, a pump for supplying fluid directly to said motor, means for by-passing the fluid to reduce the speed of the motor, and pressure responsive means automatically operable upon fluctuations in the load on the furnace for actuating the means aforementioned.

2. In a steam boiler having a furnace therefor the combination of a stoker for said furnace, a fluid operated motor for operating said stoker, a pump for supplying fluid directly to said motor, valve means for bypassing the fluid to reduce the speed of the motor, pressure responsive means connected to the steam boiler and automatically operable according to the pressure within the boiler and means connecting the pressure responsive means and the valve means whereby the valve means is controlled by the pressure responsive means.

3. In combination, a furnace having a stoker, a fluid operated motor for actuating the stoker, a pump for supplying fluid to said fluid motor, draft inducing means for the furnace including a fan, a constant speed power means for actuating both said fan and said pump, means for controlling the

output of said pump whereby the actuation of said hydraulic motor is varied, means for controlling the output of said fan and means responsive to the amount of available energy in the furnace acting to simultaneously actuate said pump output control means and said fan output control means.

In testimony whereof I affix my signature.
